George C. Henricks

UNITED STATES PATENT OFFICE

DEXTER M. WRIGHT, OF NEW YORK, N. Y.

BATON

Application filed April 12, 1930. Serial No. 443,878.

This invention relates to improvements in batons used by band leaders etc., for beating time, and it is the principal object of my invention to provide a baton of simple and therefore inexpensive construction which is light, durable highly polished and of pleasing appearance.

Another object of my invention is the provision of a baton coated with a paste of celluloid dissolved in acetone, applied to its wooden and metallic core or handle, and highly polished.

A further object of my invention is the provision of a band leader's baton equipped with a handle formed integrally therewith and encased in a cover of straps, strings or any other cover coated with a celluloid paste.

The batons made entirely of celluloid show the disadvantage that they are too flexible and therefore bend readily during their use.

It is a still further object of my invention to avoid this disadvantage by using a suitable core, while the celluloid cover for this core which may either be kept in white or any other preferred color or mottled, will give the baton a pleasing and ornamental appearance.

These and other objects and advantages of my invention will become more fully apparent as the description thereof proceeds and will then be more specifically defined in the appended claims.

In the accompanying drawing forming a material part of this disclosure:

Fig. 1 is a front and end elevation of a baton made according to my novel method and of novel construction.

Fig. 2 illustrates in sectional elevation a baton having a wooden core.

Fig. 3 is a view similar to Figure 2, illustrating a baton having a metallic core.

Fig. 4 is a fragmentary elevation of a baton with its handle shown on an enlarged scale.

Fig. 5 is a view similar to Figure 4 of a modified form of handle.

As illustrated, the baton constructed according to my invention and novel method comprises a core which may be wooden, as shown at 10, Figure 2 or metallic as illustrated in Figure 3, and designated 11. In-

tegrally made with the core are the handles 12 and 13 respectively having a larger diameter than the baton per se which is tapering towards the outer end thereof.

During the construction of the baton I cover baton and handle with a coat of celluloid, 14, preferably white, which, however, may have any other color, or mottled.

The handle constitutes preferably an enlarged part of the baton and may be made of wood or metal and covered by suitable material as for instance strings or straps as indicated at 15 in Figure 5.

The operation of my device will be entirely clear from the above description and simultaneous inspection of the drawing, and need no further explanation.

It will be understood that I have described and shown the preferred forms of my device and method only as examples of the many possible ways to practically make the same, and that I may make such changes therein as come within the scope of the appended claims without departure from the spirit of my invention and the principles involved.

Having thus described my invention what I claim as new and desire to secure by Letters Patent is:

1. A baton comprising a core, a handle formed therewith, an outer cover of straps or strings for said handle and a celluloid coating for core and handle.

2. A baton comprising a metallic core, tapering towards one end and thickened at the opposite end to form a handle, a cover for said core, and an outer highly polished coating of celluloid in paste form for said core cover.

Signed at New York, in the county of New York and State of New York, this 11th day of April, A. D. 1930.

DEXTER M. WRIGHT.
